(57) **CLAIM**

The ornamental design for a safety carabiner, as shown and described.

DESCRIPTION

FIG. 1 is a side view of a first embodiment of a safety carabiner in a first position.

FIG. 2 is a side view of the safety carabiner of FIG. 1 in a second position.

FIG. 3 is a side view of the safety carabiner of FIG. 1 in a third position.

FIG. 4 is a side view of the safety carabiner of FIG. 1 in a fourth position.

FIG. 5 is a side view of a second embodiment of a safety carabiner in a first position.

FIG. 6 is a side view of the safety carabiner of FIG. 5 in a second position.

FIG. 7 is a side view of the safety carabiner of FIG. 5 in a third position.

FIG. 8 is a side view of the safety carabiner of FIG. 5 in a fourth position.

FIG. 9 is a side view of a third embodiment of a safety carabiner in a first position.

FIG. 10 is a side view of the safety carabiner of FIG. 9 in a second position.

FIG. 11 is a side view of the safety carabiner of FIG. 9 in a third position.

FIG. 12 is a side view of the safety carabiner of FIG. 9 in a fourth position.

FIG. 13 is a side view of a fourth embodiment of a safety carabiner in a first position.

FIG. 14 is a side view of the safety carabiner of FIG. 13 in a second position.

FIG. 15 is a side view of the safety carabiner of FIG. 13 in a third position; and,

FIG. 16 is a side view of the safety carabiner of FIG. 13 in a fourth position.
